Primary Examiner — David Muller(74) *Attorney, Agent, or Firm* — Oliff PLC(57) **CLAIM**The ornamental design for a coil body for medical use, as
shown and described.

DESCRIPTION

FIG. 1 is a perspective view of a coil body for medical use;
FIG. 2 is a front view thereof;

FIG. 3 is a top view thereof;

FIG. 4 is a right-side view thereof;

FIG. 5 is a left-side view thereof;

FIG. 6 is a rear view thereof;

FIG. 7 is a bottom view thereof; and,

FIG. 8 is a cross-sectional view taken along line 8-8 of FIG.
2.The dot-dash lines depict a boundary between claimed and
unclaimed subject matter, and form no part of the claimed
design.**1 Claim, 4 Drawing Sheets**| (56) References Cited		JP	10-323395 A	12/1998
